Patented Feb. 2, 1971

219,847

CARD DIVIDER CLIP

Charles H. Nervig, Berea, Ohio, assignor to American Greeting Corporation, Cleveland, Ohio

Filed June 9, 1969, Ser. No. 17,580

Term of patent 14 years

Int. Cl. D19—99

U.S. Cl. D74—2

FIG. 1

FIG. 2

FIG. 3

FIG. 4

FIG. 5

FIG. 6

FIG. 1 is a perspective view of a card divider clip showing my design;

FIG. 2 is a side elevational view thereof;

FIG. 3 is a top plan view thereof;

FIG. 4 is a bottom plan view;

FIG. 5 is a front elevational view as seen from the left of FIG. 2; and

FIG. 6 is a rear elevational view as seen from the right of FIG. 2.

I claim:

The ornamental design for a card divider clip, substantially as shown.
